his Atty.

UNITED STATES PATENT OFFICE.

WALTER J. RUDOLPH, OF CHICAGO, ILLINOIS, ASSIGNOR TO THE IMPERIAL BRASS MANUFACTURING COMPANY, OF CHICAGO, ILLINOIS, A CORPORATION OF ILLINOIS.

PUMP FOR PRIMING, &c.

1,396,529.

Specification of Letters Patent.

Patented Nov. 8, 1921.

Application filed December 19, 1919. Serial No. 346,041.

To all whom it may concern:

Be it known that I, WALTER J. RUDOLPH; a citizen of the United States, and a resident of Chicago, in the county of Cook and State of Illinois, have invented certain new and useful Improvements in Pumps for Priming, &c., of which the following is a full, clear, and exact specification.

My invention is concerned with pumps, and more especially with priming pumps, which are usually placed on the dashboard of automobiles, and are employed to pump an extra amount of gasolene to the intake manifold for priming, etc., and is designed to produce a pump of the class described that shall be operated on the discharge stroke by spring pressure instead of positively.

It is further designed to produce a pump of the class described that will automatically close the auxiliary valve necessary in this class of pumps to prevent the suction of the engine drawing the gasolene through the check valves when the pump is not in operation.

It is further designed to produce a pump in which the tension of the spring on the intake check valve will be automatically increased when the pump is not in operation.

It is further designed to produce a pump of the class described that can be substantially completely assembled in the shop and does not need to be disassembled in installing it on the dashboard.

It is further designed to produce a pump in which the auxiliary valve shall be so constructed and mounted that it seats itself automatically and perfectly even if the seat should be somewhat out of alignment with the barrel.

It is finally concerned with certain novel details, all of which will be fully described in the specification and particularly pointed out in the claims.

To illustrate my invention, I annex hereto a sheet of drawings in which the same reference characters are used to designate identical parts in all the figures of which—

Figure 1 is a side elevation of my improved pump as it appears installed on a dashboard;

Fig. 2 is a central longitudinal section;

Figs. 3 and 4 are cross-sections on the lines 3—3 and 4—4, respectively, of Fig. 2, but on an enlarged scale.

In the ordinary use of my invention, it is installed on the dashboard 10 of an automobile by having the barrel 11 passed through a suitable aperture in said dashboard and secured by the contact of the flange 12 of the hexagonal nut 13 screwed on the end of the barrel coöperating with one side of the dashboard and the hexagonal nut 14 threaded on the barrel of the pump coöperating with the other side of the dashboard through the washer 15. The nipple 16 threaded into the inlet port body 17 and the nipple 18 similarly threaded into the outlet port body 19, both of which port bodies form a part of the end casting 20, are connected by the pipes 21 and 22 with a supply of gasolene and with the intake manifold respectively.

The barrel 11 of the pump is of the customary cylindrical construction, and one end is closed by the casting 20 which has the annular flange 21 extending over and secured to the end of the barrel in any desired manner, preferably by soldering. The other end of the barrel is closed by the end piece 23, which consists of a disk having a central aperture for the piston rod 24 with an inwardly extending annular flange 25 fitting somewhat snugly in the end of the barrel and with a smaller outwardly extending annular flange 26, which serves to shield the collar 27, which may be a hexagonal nut pinned or otherwise secured near the end of the piston rod 24, so as to prevent as far as possible anything being caught between the inner end of the collar 27 and the end of the barrel.

The end casting 20 has formed in the axial center thereof the conical valve seat 28, with which coöperates a similarly shaped valve 29, preferably formed with the annular channel 30 in the face of the conical body thereof. A rod-like extension 31 of this valve, when it is seated, extends into the adjacent end of the nipple 16, and engages and shoves inward the movable abutment 32, which is preferably a square block, and increases the tension of the helically coiled expanding spring 33 interposed between said block 32 and the ball check valve 34, which coöperates with the customary valve seat 35 in the nipple. The outlet 18 is of the customary construction and contains the helically coiled expanding spring 36 co-operating with a shoulder in the passage 110.

at one end and with the ball check valve 37 at the other end, which check valve co-operates with the valve seat 38 formed in the discharge port 39.

5 The piston rod 24 is surrounded by the strong helically coiled expanding spring 40, one end of which abuts against the end piece 23 while the other end abuts against the nut 41 which is preferably pinned to the 10 threaded end of the plunger 24. Pressed against this nut 41 by the nut 42 likewise threaded on said end is the piston 43, which may be of any desired construction, but which preferably consists of the central disk 15 44 separating the pair of cup-shaped leather washers 45 facing oppositely and held in place by the metallic cups 46 with the recessed flanges.

The nut 42 preferably has its outer face 20 concave so as to co-operate with the adjacent convex end of the valve 29, which is secured on the reduced end 47 of the piston rod in the manner best shown in Figs. 2 and 4, where it will be seen that said auxiliary 25 valve has the aperture 48 therein, somewhat larger than the reduced end 47 extending thereinto, and a pin 49 is passed through the end of the valve and through the aperture 50 in said reduced end 47, which aperture, as 30 seen in Fig. 4, is flared from the center outward in both directions, so that the valve 29 has a limited universal movement relative to the adjacent end of the piston; so that it 35 can seat itself readily and accurately on the seat 28, even if the said seat should due to inaccuracy of manufacture be slightly out of alinement with the axis of the barrel 11.

The handle 51 has a knob of some considerable size so as to make it easy for the user 40 to grasp and is screwed on the end of the piston rod 24.

The pump is completely assembled in the shop, except that the handle 51 and the nut 13 are removed, or if it is shipped with the 45 nut and handle in place, the handle can be readily removed by putting a wrench on the hexagonal collar 27 and turning the handle, and the nut 13 can of course be readily removed. When the nut 13 is removed, there 50 is no tendency for the spring to throw the end piece 23 out of the barrel, because the thrust of the spring can only operate to throw the end piece 23 outward until it contacts with the adjacent end of the collar 27, 55 which it will do before the flange 23 emerges from the end of the barrel. On account of this construction, therefore, it is an easy matter to install the pump without opening it up so as to get any dirt into it, despite the 60 presence of the spring 40.

In operation, it will be obvious that the handle 57 is drawn out, thus putting the spring 40 under tension and drawing the 65 gasoline through the nipple 16 and into the body of the barrel in the customary manner.

When the handle is released, the spring 40 forces the piston inward, opening the check valve 37 and forcing the contents down through the pipe 22 to the intake manifold. At the end of the stroke, the member 29 70 seats itself and closes the auxiliary valve, which is necessary to prevent the suction from the intake of the engine drawing the oil in past the check valve 34 and out through the discharge port 39. The channel 75 30 in the conical base of the valve makes in effect two valve seats, one for the outlet and the other for the inlet ports, and does not necessitate so perfect a grinding of the conical seat. The connections between the 80 end of the piston rod and the valve 29 are slightly loose, as previously explained, and permit the valve 29 to seat itself perfectly, while there is not sufficient movement possible so that the rod-like extension 31 can get 85 out of alinement with the large opening to the valve seat 28.

While I have shown and described my invention as embodied in the form which I consider best adapted to carry out its purposes it will be understood it is capable of modifications, and that I do not desire to be limited in the interpretation of the following claims, except as may be necessitated by the state of the prior art. 95

What I claim as new, and desire to secure by Letters Patent of the United States is:

1. In a pump, the combination with a barrel, of a closure for one end of said barrel 100 having a conical valve seat therein, inlet and outlet ports extending through said closure and one terminating in said valve seat, a piston in said barrel and a conical valve carried by the piston and having an annular 105 channel therein registering with the port terminating in the valve seat when the valve is seated.

2. In a pump, the combination with a barrel, of a closure for one end of said barrel 110 having a conical valve seat therein, inlet and outlet ports extending through said closure and one terminating in said valve seat, a piston in said barrel, a conical valve carried by the piston, having an annular 115 channel therein registering with the port terminating in the valve seat when the valve is seated, a spring associated with the barrel and put under tension by the movement of the piston to fill the barrel, and means for 120 moving the piston.

3. In a pump, the combination with a barrel, of an inlet port, a spring pressed check valve in said port, an outlet port, a piston in said barrel, means associated with 125 said piston to increase the tension of the spring of the check valve when the piston is in its normal position adjacent the ports, and a relatively powerful spring acting to return said piston to said normal position. 130

4. In a pump, the combination with a barrel, of an inlet port, a spring pressed check valve in said port, an outlet port, a piston in said barrel, means associated with said piston to increase the tension of the spring of the check valve when the piston is in its normal position adjacent the ports, a piston rod connected to said piston, and a helically coiled expanding spring surrounding said rod and interposed between the piston and the other end of the barrel.
5. In a pump, the combination with a barrel, of an inlet port co-axial with said barrel, a spring pressed check valve in said port, an outlet port, a piston in said barrel, means associated with said piston to increase the tension of the spring of the check valve when the piston is in its normal position, said means including a movable abutment in the inlet port taking the thrust of a helically coiled expanding spring interposed between it and a check valve, and a projection from the piston engaging the abutment and forcing it toward the check valve when the piston is in its normal position.
6. In a pump, the combination with a barrel, of valve controlled inlet and outlet ports, a piston associated with said barrel, an auxiliary valve seat for the inlet port, an auxiliary valve associated with the piston to close said inlet port, and a spring acting on said piston and tending to force it to its position in which the auxiliary valve is closed.
7. In a pump, the combination with a barrel, of valve controlled inlet and outlet ports, a piston associated with said barrel, an auxiliary valve seat for the outlet port, an auxiliary valve associated with the piston to close said outlet port, and a spring acting on said piston and tending to force it to its position in which the auxiliary valve is closed.
8. In a pump, the combination with a barrel, of valve controlled inlet and outlet ports, a piston associated with said barrel, an auxiliary valve seat for the inlet and outlet ports, an auxiliary valve associated with the piston to close said ports, and a spring acting on said piston and tending to force it to its position in which the auxiliary valve is closed.
9. In a pump, the combination with a barrel, provided with inlet and outlet ports, of an adjustable abutment member thereon to position the barrel, a piston mounted to reciprocate therein, a piston rod connected thereto and extending through one end of the barrel, an internally mounted closure through which the piston rod reciprocates and by which it is guided, and an external annulus removably secured on the exterior of the end of the barrel through which the piston rod moves, said annulus having a flange engaging the closure to hold it in place, and also coöperating with the abutment member to clamp a support for the barrel between them.
10. In a pump, the combination with a barrel provided with inlet and outlet ports, of a piston mounted to reciprocate therein, and a piston rod extending through one end of the barrel, said end being formed of an internally mounted closure through which the piston rod reciprocates, an external annulus removably secured on the exterior of the end of the barrel through which the piston rod moves and having a flange engaging the closure, a wrench abutment secured near the outer end of the piston rod outside of the barrel, and a handle threaded on said outer end.
11. In a pump, the combination with a barrel provided with inlet and outlet ports, of a piston mounted to reciprocate therein, a piston rod secured thereto, extending through one end of the barrel, said end consisting of a disk perforated for the piston rod and having a large annular flange projecting inwardly and fitting into the end of the barrel and a smaller annular flange projecting outwardly, an external annulus removably secured on the exterior end of the barrel through which the piston rod moves and having a flange engaging the disk, and a wrench abutment secured on the outer end of the piston rod and entering the smaller annular flange.
12. In a pump, the combination with a barrel provided with inlet and outlet ports, of a piston mounted to reciprocate therein, a piston rod secured thereto extending through one end of the barrel, said end consisting of a disk perforated for the piston rod and having a large annular flange projecting inwardly and fitting into the end of the barrel and a smaller annular flange projecting outwardly, an external annulus removably secured on the exterior of the end of the barrel through which the piston rod moves and having a flange engaging the disk, a wrench abutment secured on the outer end of the piston rod and entering the smaller annular flange, and a handle threaded on said outer end of the piston rod.
13. In a pump, the combination with a barrel provided with inlet and outlet ports, of a piston mounted to reciprocate therein, a piston rod extending through one end of the barrel, an internally mounted closure through which the piston rod reciprocates and by which it is guided, a helically coiled expanding spring introduced between said piston and said closure, a collar removably secured upon and coöperating with the adjacent end of the barrel and with said closure to hold it in place, a removable knob on the end of the piston rod, and means for preventing the accidental movement of

- said closure from the end of the barrel when the knob and the collar are removed.
14. In a pump, the combination with a barrel provided with inlet and outlet ports, of a piston mounted to reciprocate therein, a piston rod extending through one end of the barrel, an internally mounted closure through which the piston rod reciprocates and by which it is guided, a helically coiled expanding spring introduced between said piston and said closure, a collar removably secured upon and coöperating with the adjacent end of the barrel and with said closure to hold it in place, a removable knob on the end of the piston rod, and an abutment secured on the piston rod outside of the closure and tending to prevent the latter from being moved out of the barrel by the spring.
15. In a pump, the combination with a barrel provided with inlet and outlet ports, of a conical auxiliary valve seat controlling said ports, a piston reciprocating in
16. In a pump, the combination with a barrel provided with inlet and outlet ports, of a conical auxiliary valve seat controlling said ports, a piston reciprocating in said barrel, having associated therewith a concave bearing surface with a lug projecting centrally therefrom and having an aperture therethrough flaring toward both ends, and a conical auxiliary valve extension having a recess in one end into which the lug extends, and a pin passing through the aperture, and a convex bearing surface coöperating with the aforesaid concave bearing surface, substantially as and for the purpose described. 25 30 35 40

In witness whereof, I have hereunto set my hand and affixed my seal, this 16th day of December, A. D. 1919.

WALTER J. RUDOLPH. [L. S.]
Witness:
JOHN HOWARD McELROY.
